UNITED STATES PATENT OFFICE

ERVING B. MORGAN, OF GRAND RAPIDS, MICHIGAN, ASSIGNOR TO AMERICAN SEATING COMPANY, OF GRAND RAPIDS, MICHIGAN, A CORPORATION OF NEW JERSEY

LEVELING DEVICE

Application filed February 12, 1931. Serial No. 515,387.

The present invention relates to leveling devices and more particularly to devices for leveling school desk tops.

The main objects of the invention are to provide a device whereby the normally inclined top of a school desk may be readily leveled; to provide a leveling attachment adapted to be secured to the underside of a school desk top for the purpose above outlined; to provide such a device which can be readily manipulated by a child; and, to provide such a device made of two parts which may be readily assembled and after its attachment to a school desk cannot be disassembled.

An illustrative embodiment of the invention is shown in the accompanying drawing, wherein:

Figure 1 is a side elevational view of a conventional type of school desk, partly in section and partly broken away, showing the desk top held in horizontal position by the leveling device;

Figure 2 is a fragmentary front elevational view of the desk, a portion thereof being broken away to show the leveling device;

Figure 3 is an enlarged plan view of the leveling device per se showing in dotted lines its folded relation;

Figure 4 is an enlarged fragmentary side view of the leveling device secured to the underside of the desk top and taken on line 4-4 of Figure 5;

Figure 5 is an enlarged fragmentary front elevational view of the device shown in unfolded relation;

Figure 6 is a perspective view of one of the members; and

Figure 7 is a fragmentary perspective view of the other member; and

Figure 8 is an enlarged fragmentary view showing the leveling device secured to the underside of the desk top and in its folded relation.

The conventional school desk is provided with an inclined top. In the lower grades particularly, the pupils frequently work with crayons, pencils, rulers and the like which often roll or slide off of such inclined tops causing confusion and annoyance. The de-

vice herein shown and described can be conveniently manipulated by the pupil and provides means for leveling the desk top when desired as best illustrated in Figure 1 of the drawing.

Referring to the drawing, a school desk generally designated 1, is provided with a conventional normally inclined top 2 which is swingably secured along its rear edge to the desk by hinges not shown. A horizontally disposed ledge or rail 3 is secured to the inner front side of the desk in any suitable manner and provides a support for the leveling device hereinafter described.

The leveling device per se comprises a yoke 4 having spring tensioned bifurcated portions 5 and an integrally formed tongue 6 interposed between the bifurcated portions whose outer ends are provided with tensionally yielding arcuate bearing hooks 7.

A supporting strut 9 here shown as rectangular in form has a pair of spaced ears or stops 10 integrally formed at one of its ends. Between these stops is an integrally formed triangular cammed head 11.

The arcuate bearing hooks 7 embrace the strut on opposite sides of the cammed head 11 and the tongue 6 bears against the cammed head on the side opposite that embraced by the bearing hooks to hold the device in assembled relation. A screw hole 12 is provided for securing the device to the underside of the desk top in the manner best shown in Figures 1 and 4.

In operation, the supporting strut 9 is normally in folded position as is indicated by dotted lines in Figure 3. When, however, it is desired to have the desk top in leveled position as shown in Figures 1 and 2, the strut 9 is swung to the position shown in Figures 4 and 5 permitting its lower edge to rest on the ledge or rail 3 on the inside of the desk.

Figures 6 and 7 show the manner in which the two parts of the device are assembled. It will be noted that the tongue 6 is adapted to slide over the flat surface of the cammed head 11 and that the stops 10 do not prevent clearance over the hooks 7 when the strut is positioned as shown in Figure 7. When how-

ever the separate parts shown in Figures 6 and 7 are assembled and secured to the underside of the desk, the hooks 7, stops 10 and cammed head 11 prevent their separation 5 when in either their folded or unfolded relation.

It will be noted that for tensioning and quick acting purposes, the tongue bears against the triangular cammed head 11 during its swinging movement and that the spaced ears 10 act as stops for limiting the swinging movement of the strut as best shown in Figure 4. It will thus be seen that a child is able to readily level the normally inclined top of his school desk when desired.

While but one specific embodiment of this invention has been herein shown and described, it will be understood that numerous details of the construction shown may be altered or omitted without departing from the spirit of this invention as defined by the following claims.

I claim:

1. In a device of the class described, a supporting strut, a bifurcated member having an integrally formed tongue interposed between said bifurcated portions, said bifurcated member being yieldingly hingedly connected to said supporting member with said finger tensionally contacting therewith.
2. The combination with a school desk having a swingably mounted normally inclined top, of a pivotally mounted spring tensioned arm secured to the underside of said desk top adapted to be swung to a position for leveling the top.

In testimony whereof I have hereunto set my hand at Grand Rapids, Michigan, this 9th day of February, 1931.
